LATCH MECHANISM FOR SCOOPS

Victor H. Borgelt, Wisner, Nebr.

Application January 29, 1948, Serial No. 5,075

1. Claim. (Cl. 214—140)

1

This invention relates to material moving devices and more particularly to an improvement in latch mechanisms for scoops.

As is well known during shoveling operations it is desirable to have the bottom of the scoop of the material mover inclinedly disposed with respect to the surface of the ground. It is particularly desirable to have the scoop bottom adjustable for different angles of inclination in accordance with the contour of the surface of the soil.

During the scooping of a ditch or depression in the ground it is necessary that the forward end of the scoop be inclined to a greater extent than normally for scooping soil from the ditch in lieu of cutting off the shoulders of the ditch. Conversely, during removal of a hump or other convex soil surface, it is desirable to have the cutting edge of the scoop inclined upwardly.

It is also desirable that it be possible for an operator, without leaving his driving seat, to adjust the inclination of the scoop bottom. This feature is particularly desirable in the difficult scooping of debris from irrigation ditches. Such ditches are three or four feet wide and become frequently clogged with debris and loose sand which flows in with the water.

It is therefore an object of the invention to provide a latch mechanism for a scoop which will enable an operator to adjust the inclination of the scoop bottom from the driver's seat.

Another object of the invention is to provide a scoop mechanism which is adjustable as described for facilitating the formation of deep or shallow cuts.

Still another object of the invention is to provide a latch mechanism as described having other possible adjustments of the scoop-bottom inclination, such other adjustments being adapted to be made prior to making a cut or scooping operation.

Yet a further object of the invention is to provide a latch mechanism for scoops which is particularly designed for causing dumping of the latter at times when the load is so disposed as to prevent a forward dumping of the load through the over-balancing of the scoop.

Another object of the invention is to provide a device for the purpose described which is sturdy and durable in construction, reliable and efficient in operation, and relatively simple and inexpensive to manufacture, assemble and utilize.

Other and still further objects and advantages of the invention will become apparent from the

following detailed description of a preferred embodiment thereof.

In the drawings:

Figure 1 is a side elevation of the latch mechanism of the invention shown as attached to a material scooping and lifting device, the latter being secured to a tractor; the tractor and boom raising means being shown in dotted lines, a portion of the rear axle and rear axle housing being shown in full lines, certain parts of the invention being broken away and other parts showing in section;

Figure 2 is a top plan view of the mechanism shown in Figure 1;

Figure 3 is a side elevation of an enlarged detail of the latch hook and adjacent parts, certain parts thereof being broken away for revealing other parts disposed behind them;

Figure 4 is a detailed top plan view showing a set-screw arrangement which is for the purpose of regulating the tension of a spring employed as well as for further adjustment of the inclination of the scoop bottom;

Figure 5 is a detailed top plan view of the latch hook portion of the device, a connecting rod and the remainder of the scoop being broken away;

Figure 6 is a detailed side elevation of the mechanism employed for locking a hand lever in any one of several positions, the remaining portion of the lever and of a push-pull rod used being broken away; and

Figure 7 is an end elevation of the parts shown in Figure 6.

Figure 8 is an enlarged detailed assembly in top plan view of the mechanism as shown in Figure 1 for varying the angle of attack of the scoop, a dotted line position of parts shows a downwardly tilted position of the scoop.

The latch mechanism of this invention is for attachment to a material moving mechanism, including a tractor generally indicated at 10.

The tractor 10 is provided with forward wheels 12 extending downwardly from an engine housing 14, the latter being secured by means of a connecting portion 16 to a rear axle 17, a rear axle housing 18, a differential housing 20 and two rear wheels 22.

A scoop loading mechanism attached to the tractor 10 includes two parallel booms 30 extending longitudinally at either side of the tractor 10. The booms 30 are pivotally secured by means of suitable bolts 32 to ears 34 which extend forwardly from and are suitably secured to the rear axle housing 18. The booms 30 are pivotally secured at their forward ends to side plates 38 of a scoop generally indicated at 40.

A pair of right angle brackets 42 secured to the plates 38 by means of welding 44 are employed together with a pair of pivot pins 46 to secure the forward ends of the booms 30 to the scoop 40.

The pivot pins 46 are preferably so disposed with respect to the scoop 40 that the center of gravity of the scoop 40, when the latter is fully loaded, will be disposed forwardly of the pin 46.

The scoop 40 is further provided with removable side extension plates 48, which latter are attached to the back 50 of the scoop and to the outer tines 52 by means of suitable bolts 54.

The bottom 60 of the scoop 40 is also removably secured to the tines 52 by means of suitable bolts 62. As thus described the bottom 60 and sides 38 may be removed from the tines 52 at times when it is desired to scoop hay or straw in lieu of dirt or the like.

The back 50 is preferably provided with an inclined upper extension 64 extending slightly forwardly for the purpose of facilitating the retention of dirt or the like in the scoop 40.

The above described parts are old in the art and are here shown only for purposes of reference.

The latch mechanism of the invention will now be described and includes a pair of ears 71 and 72 which are longitudinally disposed with respect to the tractor in spaced apart parallelism with respect to each other. A detent or roller 74 is rotatably secured between the ears 71 and 72 by means of a pin 76 which latter extends transversely with respect to the boom 30.

The purpose of the roller 74 is to receive thereabout the tongue portion 77 and a hook portion 78 of a floating latch-hook 80. The latch hook 80 therefor has an upper surface and an under surface disposed respectively above and below the detent roller 74.

The tongue portion 77 extends forwardly of the roller 74 a considerable distance for pushing upwardly thereon to cause dumping as later described.

The roller 74 forms an engageable scoop means having two upper and lower spaced apart surfaces for engaging said latch, the surfaces being disposed transversely with respect to the length of the boom 30.

The hook portion 78 extends around the top of the roller 74 enough to prevent premature dumping of the scoop 40.

The latch-hook 80 is provided with a plurality of spaced apart apertures 84 in its lower end. The apertures 84 are disposed in a depending leg on a row extending generally vertically and transversely of the booms 30. The purposes of the apertures 84 are to receive a pin 87 therethrough for pivotally connecting the latch-hook 80 to a first arm 88 of a first bell crank mechanism.

The under surface of the hook portion of the latch hook 80, in other words the upper side of the tongue 77, is inclinedly disposed upwardly at its outer or forward end with respect to an imaginary line drawn at a right angle with respect to a second imaginary line, which latter line is disposed extending through the inner end of the said under surface and through the pivot point of the latch hook 80. The latter point can be disposed at any one of the apertures 84 as above described.

The arm 88 is rigidly secured to a shaft 90 of the bell crank mechanism. The shaft 90 is disposed transversely with respect to the booms

30 and is rotatably mounted at its inner end in a bracket 92 which latter extends forwardly from a cross bar 94.

The cross bar 94 is suitably secured to the booms 30 and extends therebetween at a right angle with respect thereto. The bracket 92 preferably extends forwardly from the cross bar 94 in parallelism with the booms 30 a fractional portion of the distance between the cross bar 94 and the rearward wall 50 of the scoop 40.

At its other and outer end the shaft 90 is rotatably mounted in an aperture through the adjacent boom 30. A second arm 98 of the bell crank mechanism extends upwardly from the shaft 90 and is normally disposed at a right angle with respect to the booms 30. The arm 98 is rigidly secured to the shaft 90.

At the upper end of the arm 98, a push-pull rod 100 is pivotally secured thereto by means of a suitable pin 102.

The push-pull rod 100 extends rearwardly alongside the adjacent boom 30 to a generally vertical lever 104, to which the push-pull rod 100 is pivotally secured at a point between the ends of the lever 104.

The lever 104 is pivotally secured to a plate 107 by means of a bolt 108. The plate 107 is itself securely attached to the upper side of the adjacent boom 30 by means of suitable bolts 110.

A plurality of circular apertures 120 are disposed through the upper end of the plate 107. The apertures 120 are arranged in the arc of a circle having its center at the pivot bolt 108. The lever 104 is provided with a lug 122 extending outwardly from that side of the lever 104 which is disposed opposite the plate 107. The lug 122 is complementary in size to the apertures 120 for receipt therein at desired times.

The bolt 108 is provided with an enlarged head 130; and a pin 132 is transversely disposed through an aperture in the bolt-head 130. The pin 132 extends through the bolt-head 130 at a right angle with respect to the bolt 108. The lever 104 is bifurcated at its lower end for providing two spaced apart parallel, apertured nibs which extend about the pin 132 on opposite sides of the bolt-head 130. A pair of coiled springs 136 and 138 are provided and are disposed about the pin 132 on either side of the bolt-head 130.

At their inner ends the springs 136 and 138 are each rigidly secured to the bifurcated ends of the lever 104. At their outer ends the springs 136 and 138 are provided with extensions 140 and 142, respectively, which latter are substantially straight and extend tangentially outwardly from their respective spring to bear against the adjacent sides of the plate 107.

Two arc-shape bearing surfaces 144 and 146 are provided and are secured to the plate 107 in such positions as to engage the ends 140 and 142 during pivotal movement of the lever 104 about the bolt 108.

The plate 107 is provided with a foot portion 150 disposed at a right angle thereto, the foot portion 150 having suitable apertures 152 therethrough for receiving the above described bolts 110.

The purpose of the lever 104 and attached parts is to adjust the spacing of the jaws of the latch-hook 80 with respect to the booms 30 for adjusting the position of the forward end of the scoop 40 with respect to the booms 30. It will be seen that by attaching the bell crank arm 88 to different ones of the apertures 84, fur-

ther and pre-determined adjustments may be made.

Means for releasing the latch-hook 80 from the roller 74 are provided and will now be described. Such means include a second bell crank or rocker shaft 160 disposed longitudinally with respect to the cross bar 94.

The shaft 160 is rotatably secured to the cross bar 94 by means of suitable mountings 162 adjacent each of its ends. A vertically extending 10 arm 164 is secured to the second bell crank shaft 160 at its lower end. The upper end of the arm 164 is provided with a suitable aperture 166 for receiving a connecting rod 168.

The connecting rod 168 is secured to the arm 15 164 at its rearward end and is hooked through a desired one of a plurality of holes 170 in the latch-hook 80 at the forward end of the connecting rod 168. The holes 170 are spaced apart and disposed in a row extending transversely away from the booms 30, certain of the holes 170 being disposed further away from the lever 190 and the aperture 166 than others of the holes 170. The purpose of the holes 170 will be later described.

A lever 190 is provided and is disposed transversely with respect to the booms 30 extending upwardly therefrom. The lever 190 is provided with an eyelet 192 at its upper end for the reception of a pull rope 194. The rearward end of the pull rope 194 extends to within reach of the operator of the tractor 10 while sitting in the driver's seat.

The lower end of the lever 190 is rigidly secured to the second bell crank shaft 160. A piece of angle iron 196 is secured to the lever 190 adjacent the lower end thereof and the angle iron 196 extends transversely with respect to the lever 190, being normally disposed in a position generally parallel to the upper side of the adjacent boom 30. A set-screw 200 is threadedly disposed through a threaded aperture in the angle iron 196.

The purpose of the set-screw 200 is to adjust the relative position of the angle iron 196 and the adjacent boom 30 for regulating the forward position of the lever 192 and for regulating the tension of a later described coiled spring 220.

The coiled spring 220 is of a tension type being secured to the lever 190 at a point between the ends of the latter by means of eyelets 222 and 224. The spring 220 extends forwardly and downwardly from the lever 190 at an angle with respect thereto and is secured at its lower end to the adjacent boom 30 by means of a suitable eyelet 230.

In operation and during shoveling movements, the spring 220 will tend to maintain the latch-hook 80 about the roller 74 for locking the scoop 40 in shoveling position with respect to the surface of the ground 250, as best shown in Figure 1.

When it is desired to lower the forward end of the scoop 40 with respect to the booms 30 during shoveling movement, the operator may readily do so by urging forwardly on the lever 104. This will in turn operate through the first described bell crank mechanism for elevating the latch-hook 80 with respect to the booms 30.

Such elevating motion will cause the scoop 40 to rotate clockwise about its pivot pins 46 as best shown in Figure 1, thus urging the forward end of the scoop 40 downwardly.

When it is desired to raise the relative position of the forward end of the scoop 40 with respect to the boom 30, a similar but reverse move-

ment is initiated by pulling rearwardly upon the lever 104, thus moving the rod 100 in the direction of the arrow 300, as best seen in Figure 8, to place the scoop in the dotted line position. It will be seen that, prior to operation, further adjustments may be made by attaching the arm 88 to different ones of the apertures 84. Thus, the attachment of the arm 88 to an upper one of the apertures 84 will cause a corresponding raising of the forward end of the scoop 40 with respect to the booms 30 and vice versa.

During shoveling movements, counterclockwise rotation of the scoop 40 will be prevented through the action of the spring 220.

Further adjustments in the positioning of the scoop 40 with respect to the booms 30 may be accomplished through the adjustment of the set-screw 200, through the insertion of the connecting rod 168 through different ones of the apertures 170, through the attachment of the arm 88 to different ones of the apertures 84, and by inserting the lug 122 of the lever 104 in different ones of the apertures 120.

The scoop 40 is pivotally mounted by the pins 46 and the only other means of retaining the scoop horizontal or at different angles is the roller 74 and the latch hook 80 and the latch hook is tilted upwardly or downwardly by the link 168, which is held by the spring 220 through the bell crank shaft 160, whereby adjustment of the set screw 200 regulates the tilting positions of the scoop.

When the scoop 40 is loaded, the booms 30 are elevated and the tractor 10 is caused to propel the load to a desired destination. When it is desired to dump the scoop 40 the operator will pull rearwardly on the lever 190 and rope 194.

This, in turn, will pull rearwardly on the latch-hook 80 against the urge of the spring 220, disengaging the latch-hook 80 from the roller 74 and permitting dumping of the load.

The load is caused to dump since it will usually over-balance the scoop 40 forwardly of the pivot 46. Should the load be so disposed that the scoop will not over-balance, it will dump anyway due to the upward thrust of the tongue portion 77 of the latch-hook 80.

Following dumping, as the booms 30 are again lowered into shoveling position, the forward end of the scoop 40 will strike the ground first causing the scoop to pivot counterclockwise as shown in Figure 1. As the roller 74 strikes the tongue 77 it will automatically become lodged between the tongue 77 and the hook portion 36 for preventing further rotation of the scoop in either direction.

This invention has provided latch mechanism for scoops which holds a scoop in fixed position with respect to its booms, permits quick dumping, and which is particularly adapted for the adjustment of the angle of inclination of the bottom of the scoop with respect to its booms both during and prior to shoveling operation.

From the foregoing description, it is thought to be obvious that a latch mechanism for scoops constructed in accordance with my invention is particularly adapted for use by reason of the convenience and facility with which it may be assembled and operated, and it will also be obvious that my invention is susceptible of some change and modification including variations in the shape and size of the parts without departing from the principles and spirit thereof, and for this reason I do not wish to be understood as limiting myself to the precise arrangement and

formation of the several parts herein shown in carrying out my invention in practice, except as claimed.

I claim:

In a scoop latch, the combination which comprises spaced parallel longitudinally disposed booms for use on a tractor, a scoop having a back, side plates, tines, and a bottom positioned between said booms, brackets extended from said side plates, pivot pins extended through the brackets, side plates and booms pivotally mounting the scoop in the booms, a cross bar connecting the booms and spaced from the scoop, spaced ears extended from the back of the scoop, a roller positioned between said ears, a pin extended through the roller and ears for journaling the roller in the ears, a floating latch-hook positioned whereby parts thereof extend between said ears, said latch-hook having a hook portion positioned to extend over said roller and a tongue portion positioned to extend below said roller, said tongue portion extended beyond the roller to facilitate elevating the scoop in dumping and providing a guide to direct said roller into said latch-hook in latching said scoop in an operative position, said latch-hook having a depending leg with spaced openings therein positioned substantially at a right angle to said tongue portion and at an acute angle in relation to a plane perpendicular to said booms and parallel to the upper edge of said latch-hook, a bell-crank shaft positioned between the cross bar and scoop and mounted with one end pivotally mounted in one of said booms and the other pivotally mounted in a bracket extended from said cross bar, a first arm extended from said bell-crank shaft, a pin pivotally connecting said first arm to the depending leg of said latch-hook,

a second arm extended from said bell-crank shaft and positioned at an angle of substantially 90° in relation to the first arm, a push-pull rod pivotally connected to said second arm, a rocker shaft journaled on said cross bar, a lever extended upwardly from said rocker shaft, positioned adjacent the boom in which the bell-crank shaft is pivotally mounted, and having an eye on the upper end for receiving a rope, a vertically disposed arm carried by said rocker shaft and positioned in alignment with said latch-hook, a rod connecting said vertically disposed arm to said latch-hook, said latch-hook having a plurality of spaced openings therein for receiving said connecting rod, a spring connected at one end to said lever and at the other to said boom adjacent which the lever is positioned, and a set screw carried by said lever and positioned to engage said boom for adjusting the return position of said latch-hook.

VICTOR H. BORGELT.
